United States Patent

Des. 240,301
Patented June 15, 1976

240,301

MAGNETIC VIDEO REPRODUCER

Takao Takanashi, Tokyo, Japan, assignor to
Sony Corporation, Tokyo, Japan

Filed Jan. 20, 1975, Ser. No. 542,418

Claims priority, application Japan July 22, 1974

Term of patent 14 years

Int. Cl. D14—01

U.S. Cl. D26—14 B

FIG. 1

FIG. 1 is a front perspective view of a magnetic video reproducer embodying my design.

FIG. 2 is a rear view of the device illustrated in FIG. 1.

FIG. 3 is a side view similarly illustrating the side of the device which is not seen in FIG. 1.

I claim:

The ornamental design for a magnetic video reproducer, as shown.
